Inventor
Algermont H. Waldo
By Nixon & Crane
Attnys.

UNITED STATES PATENT OFFICE.

ALGERMONT H. WALDO, OF ST. PAUL, MINNESOTA.

DESIGN FOR A RUG.

Application filed April 21, 1924. Serial No. 9,346. Term of patent 3½ years.

To all whom it may concern:

Be it known that I, ALGERMONT H. WALDO, a citizen of the United States, residing at St. Paul, in the county of Ramsey and State of Minnesota, have invented a new, original, and ornamental Design for Rugs, of which the following is a specification, reference being had to the accompanying drawing, forming a part thereof.

The figure is a plan view of a rug showing my design.

I claim:

The ornamental design for a rug, as shown.

St. Paul, Minnesota, April 16, 1924.

ALGERMONT H. WALDO.
